UNITED STATES PATENT OFFICE.

NAPOLEON SHOREY AND FRANCIS P. FLYNN, OF WOODLAND, MAINE.

SUCTION-BOX.

1,216,861.

Specification of Letters Patent. Patented Feb. 20, 1917.

Application filed June 7, 1916. Serial No. 102,318.

To all whom it may concern:

Be it known that we, NAPOLEON SHOREY and FRANCIS P. FLYNN, citizens of the United States, both residing at Woodland, 5 in the county of Washington and State of Maine, have invented certain new and useful Improvements in Suction-Boxes; and we do hereby declare the following to be a full, clear, and exact description of the invention, 10 such as will enable others skilled in the art to which it appertains to make and use the same.

The present invention relates to improvements in suction boxes such as are used on 15 Fourdrinier machines, and more specifically the invention consists in improvements in suction box tops which are provided with perforations for permitting air and moisture to be drawn therethrough by the pump apparatus and through the wire conveyer which passes over the suction box tops in a 20 well known manner.

Broadly stated, the present invention contemplates the supplying to the under side of 25 the wire conveyer, on which the pulp is carried, a lubricant immediately prior to passing over the suction box tops, whereby such passage will be facilitated and the friction therebetween reduced.

30 It is among the further objects of the invention to provide the suction box top with metallic inserts or reinforces, upon which will devolve the function of taking up the friction created by the passing of the wire 35 and which will have the effect of preventing grooving of the box tops in the manner at present found so troublesome and expensive.

In the accompanying drawings forming a 40 part of this application, and in which similar reference symbols indicate corresponding parts in the several views:

Figure 1 is a top plan view of an improved suction box as constructed in accordance with the present invention; and

45 Fig. 2 is a cross sectional view taken on the line 2-2 in Fig. 1.

Referring more particularly to the drawings, wherein one embodiment of the present invention is illustrated, at 1 is designated

one of the usual suction boxes, which at 50 present is constructed of metal and mounted on the Fourdrinier machine in a manner which will be apparent to those skilled in this art. The box may be equipped with the usual movable heads for well known purposes, and the same is connected up to a suction producing apparatus after the approved 55 fashion.

The tops of the suction boxes as now constructed are of wood, perforated to admit 60 air drawn by the suction apparatus from the atmosphere through the pulp or other material on the wire conveyer which is indicated at 2, and which is trained over the breast, couch, and table rolls, these not being 65 shown, as forming no part of the present invention.

With wooden tops as presently employed, great difficulty is experienced in securing the 70 free passage of the conveyer 2 thereover, inasmuch as the passage of such wire, which is extremely heavy with the weight of the pulp or other material carried, is found, in practice, to produce grooves in the box tops, thereby 75 destroying the uniformity of the surface over which the wire must pass. By reason of the action of the suction in drawing the wire into close contact with the box tops, the inequality produced by the grooving becomes a serious obstacle to the proper 80 operation of the wire, creating unusual friction between these parts, decreasing the life both of the wire and box tops, and requiring an increased amount of power to draw such wire over the suction boxes.

In order to obviate the above and other 85 difficulties in the operation of the wire over suction boxes, the box covers or tops 3, which may be constructed of wood in the usual manner, are grooved to receive triangular 90 or V-shaped insertions or reinforces 4, which are advantageously chilled upon their upper surfaces so as to resist to a high degree the action of friction. It is to be understood, however, that, while such insertions or reinforces 95 4 may be of chilled metal, the same may be of other material found suitable in practice for this purpose, and we do not

wish ourselves understood as restricting the invention to the use of chilled or other metal.

The box top 3 is traversed by the usual perforations 5, and the insertions or reinforcements 4 may also, if desired, be perforated as indicated at 6. The perforations 6 in the reinforcements 4, while they are shown in Fig. 1, to be of smaller diameter than the perforations 5, in order not to reduce to too great an extent the area of the friction surfaces, are nevertheless of practical utility in affording an increased surface exposure to the action of the suction in order that all parts of the pulp or other material carried by the wire, may be effectively dried.

The reinforcements 4, as shown in the present drawings, may be stamped out from a sheet of metal, leaving a longitudinal strip 7 running lengthwise of the suction box and being common to all of such reinforcements; the strip 7 being secured as by screws 8 or other means to the top 3 of the box. The strip 7 is formed with a flange 9, illustrated more particularly in Fig. 2 to be turned down over the longitudinal edge of the cover 3 and secured thereto as by screws or other means 10. At their apexes the inserts 4 may be further secured to the top 3 of the box 1 by screws or other fastening means 11, and preferably have their extremities turned down against the adjacent edge of the cover 3, as indicated at 12 in Fig. 2, where recesses are provided to receive the same, so that the inserts as a whole may lie flush in the cover 3 and form a continuous and unbroken surface therewith.

It will be understood that the reinforcements 4 will preserve the top 3 of the suction box and will prevent grooving by the action of the wire 2 in its passage over the same, and will also reduce the friction to a minimum to prolong the life both of the wire and box covers. While this construction in itself may be employed with excellent results to constitute a substantial improvement over the present form of suction box covers, the action of the wire in passing over the box cover 3 with the reinforcements 4 may be facilitated by supplying to the under side of the wire a lubricant, such, for instance, as water.

For this purpose a trough 13, advantageously of sheet metal, although we do not wish to be confined to this material, is secured preferably to the box cover 3 by the fastening means 10 for holding the flange 9, the edge of the trough 13 being inserted beneath said flange as see Fig. 2. Through the heads 14 and 15, of the trough, passes a pipe 16 having minute orifices 17 therein, such pipe 16 being in communication with a source of water supply which is delivered to the under side of the wire 2 by being sprayed thereon in small jets.

If desired, a slight flow from the trough

13 may be induced onto the cover 3 of the box 1 by providing the edge 18 of the trough 13 at a slightly higher level than the top of the suction box 3, and by maintaining the liquid level in said trough 13 at a proper height. Thus the wire 2 may also come into contact with the water surface in the trough 13, receiving its lubricant before passing over the box top 3.

It is to be appreciated that the lubricating device as herein shown may be employed to lubricate wires in their passage across suction box tops as now constructed; or may be used in conjunction with the improved suction box top with the reinforcements as herein described; and likewise, the improved suction box top, in accordance with the present invention, may be employed either alone or in conjunction with the water supply device as may be found desirable or necessary in practice.

It is obvious that those skilled in the art may vary the details of construction and arrangements of parts without departing from the spirit of our invention, and therefore we do not wish to be limited to such features except as may be required by the claims.

We claim:

1. A suction box including a top, and reinforcements secured to said top, substantially as described.

2. The combination with a conveyer, of a suction box having a top, and reinforcements set flush in said top, substantially as described.

3. The combination with a metallic conveyer, of a suction box having a perforated wooden top, and metal reinforcements mounted flush in said top for receiving the wire conveyer, substantially as described.

4. The combination with a conveyer, of a suction box having a perforated top over which said conveyer is arranged to travel, and means for supplying a lubricant to the conveyer, substantially as described.

5. The combination with a conveyer, of a suction box having a perforated top for receiving said conveyer, and means for spraying a lubricant onto the under side of said conveyer, substantially as described.

6. The combination with a conveyer, of a suction box having a perforated top for receiving said conveyer, a trough secured to one side of said suction box, and a perforated pipe in said trough for spraying a lubricant onto the under side of said conveyer, substantially as described.

7. The combination with a conveyer, of a suction box having a perforated top, reinforcements in said top for contacting with said conveyer, and means for spraying water onto the under side of said conveyer prior to its passage over said box, substantially as described.

8. In combination with a conveyer, of a

suction box having a perforated top, metallic triangular reinforces set flush in said top, a trough secured to one side of said box, and a perforated pipe in communication with a source of water supply for spraying water onto the under side of said wire prior to its

passage over said suction box, substantially as described.

In testimony whereof, we affix our signatures.

NAPOLEON SHOREY.
FRANCIS P. FLYNN.
